UNITED STATES PATENT OFFICE.

PETER ANTHONY VEILEX, OF LA CANADA, CALIFORNIA.

BOOK, LEAF, OR MUSIC HOLDER.

SPECIFICATION forming part of Letters Patent No. 634,781, dated October 10, 1899.

Application filed March 2, 1899. Serial No. 707,436. (No model.)

To all whom it may concern.

Be it known that I, PETER ANTHONY VEILEX, a citizen of France, residing at La Cañada, in the county of Los Angeles and State of California, have invented new and useful Improvements in Devices for Holding Books, Leaves, or Music, of which the following is a specification.

My invention has relation particularly to devices employed (while playing on musical instruments) to hold the leaves of books and music open while being read; and the object is to provide a device which will hold the leaves of the book or music open without the use of the fingers that they may be otherwise employed in playing the instrument or in turning the leaves of the music-book, preventing the annoyance to the performer of having the leaves of the book or music continually closing, which is apt to occur if the leaves are not held in the open position. I accomplish these objects by means of the device herein described and shown in the accompanying drawings, in which—

Figure 1 is a front view thereof with a book in place thereon and the leaves of the same being held open by the leaf-detaining fingers D. Fig. 2 is a rear perspective view of the same, showing the manner in which it is held in position on the instrument. Fig. 3 is an enlarged plan view of the leaf-retaining finger D. Fig. 4 is an enlarged side view of the finger D, showing the manner of its attachment to the frame.

In the drawings, A represents the frame of the holder, and B the bed of the same.

E is a swinging support hinged at L, the limit of its movement being regulated by the adjusting-cord F, which is made fast to the frame A at the bottom thereof, thence passing out through the bottom B, thence through a hole in the free end of the support E, and thence up and over the catch E'. By letting out the adjusting-cord the free end of the support E will be thrown back and away from the frame and give greater inclination to the face of the frame and to any book or music resting thereon. Now if this cord is taken up the frame will assume a more vertical position, wherefore it is manifest that any desired angle can

be given to the face of the device by the manipulation of the adjusting-cord.

When it is desired to use the holder, it is put in the desired place on the instrument and the pivoted support E is given the desired angle to the frame A, when the adjusting-cord is made fast by passing the free end thereof over the catch E' and pulled firmly thereto. The book or music, as C, to be read is then placed on the bed of the holder, and the free ends of the detaining-fingers are moved over the face of the leaves into the position shown in Fig. 1. The fingers D are mounted on and form a continuation of the free end of a coiled spring I, which is coiled around a bolt J, the other end of the spring resting on the swinging plate K. The tendency of this spring is to hold the finger D in the position shown in full lines in Fig. 4. The swinging plates K are provided with bearings for the bolts J and also with lugs k. These lugs project out from the plates and between which the fingers D have an up-and-down movement. These plates are pivotally attached to the frame by means of screw-threaded bolt H, which passes through the frame and thence through the hole K' in the plate K, and a clamping-nut G is screwed onto the end of the bolt H. This nut by being screwed sufficiently tight will hold the finger in position and prevent any swinging movement of the plate K, except when the positive motion is imparted to the finger D by the operator. The space between the shank D' of the finger D (see Fig. 4) and the frame A should be ample to permit the performer to pass his forefinger under the leaf-retaining finger when it is desired to move the same. By placing the thumb on the frame and running the forefinger under the leaf-retaining finger it can be pulled back and away from the leaf and moved into any desired position with facility.

Having described my invention, what I claim as new, and desire to secure by Letters Patent, is—

The combination in a music-holder, of the frame A; the leaf-detaining fingers D; the coil-spring I encircling the bolt J, the free end of said spring rigidly affixed to said fingers, and the other end of said spring arranged to

2
press against the plate K, the bolt J forming bearing for coiled spring; the plate K having bearing for bolt J, and lugs *k* integral therewith and projecting out of the same; the plate 5 removably attached to the frame by bolt H; the screw-threaded bolt H, having adjusting-nut G; the swinging support E hinged to the top of the frame, and the adjusting-cord fas-

tened to the bottom of the frame and adjustably attached to the bottom of the support 10 E, substantially as shown and described.

PETER ANTHONY VEILEX.
